UNITED STATES PATENT OFFICE.

BESTIANE D. ROSS, OF BROCKWAYVILLE, PENNSYLVANIA.

GATE OPERATING AND LOCKING MECHANISM.

Application filed January 5, 1923. Serial No. 610,829.

To all whom it may concern:

Be it known that I, BESTIANE D. Ross, a citizen of the United States, residing at Brockwayville, in the county of Jefferson and State of Pennsylvania, have invented certain new and useful Improvements in Gate Operating and Locking Mechanisms, of which the following is a specification, reference being had to the accompanying drawings.

This invention relates to certain improvements in gate operating and locking mechanisms and has relation more particularly to a mechanism of this general character especially designed and adapted for use in connection with double doors and it is an object of the invention to provide such a mechanism having novel and improved means whereby the doors may be caused to operate to move in unison together with means for effectively holding or locking said doors when in either open or closed position.

Another object of the invention is to provide a novel and improved device of this general character comprising a carriage operatively engaged with the doors whereby the doors are caused to move in unison together with means associated with the carriage for holding the doors when in either open or closed position.

Another object of the invention is to provide a novel and improved mechanism of this general character embodying means for causing a plurality of doors to move in unison together with additional means for locking the doors when in closed position.

The invention consists in the details of construction and in the combination and arrangement of the several parts of my improved gate operating and locking mechanism whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a vertical sectional view with parts in elevation illustrating a mechanism

constructed in accordance with an embodiment of my invention, the single door shown being in closed position;

Figure 2 is a fragmentary view partly in elevation and partly in section of the carriage and track as illustrated in Figure 1, said view being reverse to what is illustrated in Figure 1;

Figure 3 is a detail sectional view taken substantially on the line 3—3 of Figure 1 looking in the direction of the arrow;

Figure 4 is a view partly in top plan and partly in horizontal section illustrating my improved mechanism with the associated doors in closed position, a second position of the doors being diagrammatically indicated by broken lines;

Figure 5 is a detail sectional view taken substantially on the line 5—5 of Figure 1 looking in the direction of the arrow;

Figure 6 is an enlarged fragmentary view partly in elevation and partly in section illustrating the locking mechanism as herein comprised;

As disclosed in the accompanying drawings, D denotes a pair of swinging doors of a type particularly adapted for use in connection with garages or kindred structures and a detailed construction of which forms no particular part of my present invention. Supported inwardly of the doors as by the rafters 1 or the like is a track-way T of desired length, said trackway being herein disclosed as held in applied position by the brackets 2.

The track-way T is substantially H-form in cross section and traveling along said track-way is a carriage C provided adjacent its opposite ends with the transversely spaced flanged wheel 3 directly engaging the track-way. The carriage C also embodies the side plates 4 arranged outwardly of the track-way T and extending therebelow. The lower portions of the side plates 4 have interposed therebetween and secured thereto, as by the rivets 5 or the like the plate 6, said plate underlying the track-way T.

Extending outwardly and laterally from each of the side plates 4 is a pair of vertically spaced arms 7 between which is pivotally engaged the flattened head 8 operatively engaged with the end portion of a tubular member 9. The member 9 is of desired length and has its opposite end portion pro-

vided with a second flattened head 10 which extends between and pivotally engages with a vertically spaced pair of arms 11 carried by a bracket 12, said bracket 12 being suitably anchored to the upper portion of a door D at a point in relatively close proximity to its outer or free vertical margin.

The rods 9 provide means whereby the carriage C causes both of the doors D to swing in unison into either open or closed position and irrespective of which of the two doors may be subjected to the requisite push or pull.

Freely or loosely engaged with one of the axles 14 of the carriage C is an end portion of a vertically swinging arm 15 the outer or free end portion of which terminating in a depending lug or flange 16. The arm 15, as is clearly illustrated in Figure 1 overlies the second axle 14 of the carriage C to positively limit the downward swinging movement of said arm 15.

When the doors D are in closed position as illustrated in Figures 1 and 3 the lug or flange 16 seats within a groove or recess 17 formed in the upper face of a block 18. The upper surface of the block 18 before and aft of the recess or notch 17 is disposed on an upward and inward incline so that as the carriage passes over the block 18 the lug or flange 16 of the arm 15 will be readily received within the recess or notch 17. When the lug or flange 16 is so engaged within the notch or recess 17 the doors D are held against outward or opening movement.

When the doors D are at the limit of their outward or opening movement the lug or flange 16 of the arm 15 engaged within the recess or notch 19 produced in the upper surface of a block 20, said upper surface of the block 18 before and aft of the notch or recess 19 being also disposed on an upward or inward incline to facilitate the entrance of the lug or flange 16 within said notch or recess.

Underlying the block 20 is a block 21 herein disclosed as secured to the block 20 by the coacting bolts and nuts 22. The bolts being disposed through a suitably positioned elongated slot 23 formed in the web of the track-way T. The slot 23 provides means whereby the blocks 20 and 21 may be adjusted lengthwise of the track-way T as the necessities of practice may require.

The block 21 is provided with a depending and inwardly facing shoulder 24 with which the plate 6 of the carriage C is adapted to contact and whereby the extent of outward or opening movement of the doors D is positively limited.

The block 18, hereinbefore referred to, is held to the web of the track-way T by the coacting bolts and nuts 25, the bolts being also disposed through a suitably positioned

slot 23 whereby the position of the block 18 may be adjusted lengthwise of the track-way T as desired.

It is preferred in producing the track-way T to have a plurality of slots 23 produced in the web at predetermined points spaced longitudinally thereof so that in applying my improved mechanism the blocks 18, 20 and 21 may be readily and conveniently located upon the track-way T as desired.

The arm 15 together with the lug or flange 6 carried thereby normally swings downwardly by gravity. Depending from one of the pipes 9 adjacent an associated head 8 is a pair of spaced arms 26 between which is pivotally engaged as at 27 the wheel portion of a bell crank lever L. One arm 28 of the lever L underlies a vertically disposed rod 29 having free sliding movement through a tubular bolt 30, said bolt 30 also serving as a pivot between a head 8 and a pair of arms 7. This rod also underlies an outstanding and laterally disposed wing 31 carried by the arm 15 at a point between the axles or shafts 14 of the carriage C. Upon upward swinging movement of the arm 28 of the lever L the rod 29 may also be forced upward and by contact of the arm 29 with the associated wing 31 the arm 15 will be raised sufficiently to disengage or free the lug or flange 16 from either a block 18 or a block 20 so that the doors D will be free to swing into open or closed position.

The second arm 32 of the bell crank lever L extends upwardly within the adjacent pipe 9 through a suitably positioned slot 33 provided in the wall of said pipe and the inserted end portion of the arm 32 is operatively engaged with a rod 34 extending through the pipe 9 and also operatively engaged with an inserted end portion of an upstanding arm 35 of a second bell crank lever B. This lever B has its wheel portion pivotally supported as at 36 between a pair of arms 37 depending from the outer end portion of the pipe 9 and the second arm 38 of the lever B is disposed in a direction toward the door D.

The outer end portion of the arm 38 is operatively engaged as at 39 through the instrumentality of a chain or other flexible means with the upper end portion of a vertically disposed rod 40. This rod 40 is preferably sectional with its adjacent end portions coupled by a turn-buckle 41 so that the rod 40 may be lengthened or shortened as the occasions of practice may require when applying my improved mechanism and whereby the mechanism is maintained substantially free of rattle and without undue lost motion.

The lower portion of the rod 40 is provided with a bar 42. This bar 42 is slidably disposed within a casing 43 through the top thereof and the inserted end portion of this

- bar 42 is operatively engaged with a rock member 44. The arm 42 within the casing 43 is provided with a laterally directed arm 45 which operatively engages through the 5 medium of the rigid plate 46 with the end portion of a rock lever 47. The opposite end portion of the lever 47 is operatively engaged with a second bar 48 which has free sliding movement through the lower portion 10 of the casing 43 and the outer or lower end portion of said rod 48 is operatively engaged with the upper end portion of a rod 49. This rod 49 is also sectional and has the opposed end portions of its sections coupled 15 by the turn-buckle 50 for the same purposes as hereinbefore set forth with respect to the turn-buckle 41.
- The lower end portion of the rod 49 is operatively engaged as at 51 with the latch 20 52. This latch 52, when the doors D are in their full closed position, engages a keeper 53 provided in the floor of the garage or other structure whereby the doors D are further held in closed position.
- 25 Disposed through the casing 43 and extending beyond the opposite sides of the associated doors D is a spindle 54, the extended or exterior portions of said spindle having suitably affixed thereto the operating 30 members 55, whereby requisite turning or rocking movement may be imparted to the spindle 54 outside of the garage or other structure or from within. Carried by the spindle 54 within the casing 43 is a cam 35 member 56 which, upon requisite rocking movement of the spindle 54 serves to impart the desired rocking movement to the rock member 44 and which movement results in a simultaneous inward pull being interposed 40 upon the bars 42 and 48 resulting in retraction of the latch 52 and upward swinging movement of the arm 28 of the lever L to free the flange or lug 16 from either the block 18 or 21. Under these conditions the 45 doors are then free to be moved in either open or closed position.
- With the doors D in either open or closed position it is of advantage to positively lock the same in such position and for this purpose I shall provide within the casing 43 a key actuated bolt 57 which interlocks with the bar 48 when said bar has been moved inwardly of the casing 43.
- From the foregoing description it is 55 thought to be obvious that a gate operating and locking mechanism constructed in accordance with my invention is particularly well adapted for use by reason of the convenience and facility with which it may be 60 assembled and operated, and it will also be obvious that my invention is susceptible of some change and modification without departing from the principles and spirit thereof and for this reason I do not wish to be 65 understood as limiting myself to the precise arrangement and formation of the several parts herein shown in carrying out my invention in practice except as hereinafter claimed.
- I claim:
1. In combination with a pair of swinging doors, a track-way supported adjacent thereof, a carriage travelling on the track-way, tubular members operatively connected with the carriage and the doors to cause said doors to move in unison into either open or closed position, a latch carried by the carriage, means carried by the track-way with which the latch engages when the doors are in either open or closed position, a rod carried by the carriage and contacting upon movement in one direction with the latch to move the latch into inoperative position, a bell crank lever supported for 70 rocking movement by one of the tubular members, one arm of the lever upon movement of the lever in one direction contacting with the rod to cause the same to engage the latch, a second arm of the bell crank lever extending within the tubular member, a second bell crank lever carried by said tubular member adjacent its connection with the door, an arm of said second lever also extending within the tubular member, an operative connection between both of the bell crank levers extending through the tubular member, an operating member carried by one of the doors, and an operative 75 connection between said operating member and the second arm of the second bell crank lever.
  2. In combination with a pair of swinging doors, a track-way supported adjacent thereto, a carriage travelling on the track-way, tubular members operatively connected with the carriage and the doors to cause said doors to move in unison into either open or closed position, a latch carried by the carriage, means carried by the track-way with which the latch engages when the doors are 80 in either open or closed position, a rod carried by the carriage and contacting upon movement in one direction with the latch to move the latch into inoperative position, a bell crank lever supported for rocking movement by one of the tubular members, one arm of the lever upon movement of the lever in one direction contacting with the rod to cause the same to engage the latch, a second arm of the bell crank lever extending within the tubular member, a second bell crank lever carried by said tubular member adjacent its connection with the door, an arm of said second lever also extending within the tubular member, an operative connection between both of the bell crank levers extending through the tubular member, an operating member carried by one of the doors, and an operative 85 connection between said operating member and the second arm of the second bell crank lever.

of the second bell crank lever, and means for locking the operating member.

3. In combination with a pair of swinging doors, a track-way supported adjacent said doors, a carriage travelling on the track way, an operative connection between the carriage and each of the doors to cause said doors to move in unison into either open or closed position, coacting means carried by the carriage and the track-way for holding the doors in either open or closed position, means carried by one of the doors and

operatively engaged with the holding means for rendering the same inoperative to permit the doors to be moved in either open or closed position, additional means for holding the doors in closed position, and means operated by the means for rendering the first-named holding means inoperative to release the last named holding means. 15 20

In testimony whereof I hereunto affix my signature.

BESTIANE D. ROSS.
